BODY DRAG

Filed Aug. 20, 1928

Timothy J. Dilworth
INVENTOR.

UNITED STATES PATENT OFFICE

TIMOTHY J. DILWORTH, OF BOSTON, MASSACHUSETTS

BODY DRAG

Application filed August 20, 1928. Serial No. 300,861.

My invention is a device for the recovery of bodies lost by drowning in harbors, bays, lakes or rivers.

The devices now in use for this purpose are haphazard arrangements which very often slip entirely over the body sought to be recovered without catching in any part of it; they are also rendered ineffectual by the presence of eel-grass and other bottom growths which generally cause the devices to become tangled up in themselves.

It is accordingly the purpose of my invention to recover the body sought by the use of a frame from which project a number of hooks which are rigidly affixed to the frame in such a way as to make fouling impossible.

This frame is lowered to the bottom by means of a rope. By dragging the frame along the bottom at an angle of 45 degrees the bends of the hooks ride along the bottom, thus leaving the points free to become firmly imbedded in the clothing of the body.

In my invention the arrangement of the hooks and the method by which they are attached to the frame make the entire drag reversible, so that care need not be exercised that the drag is lowered to the bottom with the proper side down.

With the above objects in view the invention resides in certain details of construction as will hereinafter be more fully described and claimed.

In the drawing Fig. 1 is a front elevation of my invention.

Fig. 2 is a side elevation showing the method of attaching the hooks to the frame.

My invention consists of two pieces of round iron 3—3, in the shape of an inverted letter V with an eye 4 in each piece of round iron at the apex of the V for the insertion of a drag rope. The outer ends of the round iron are screwed into a piece of angle iron, 2, and secured by nuts, 5—5; to this piece of angle iron, 2, are affixed by stove bolts, 6, alternately two-inch and five-inch double-pointed, barbed hooks, 1—1—1, which are spaced five inches apart; nine hooks taking up the width of the frame. In order to make the hooks double-pointed, in each case, two

single hooks are joined back to back by solder, 7.

It is in this way that the entire drag is made reversible; bolting the hooks to the angle iron makes it easy at any time to replace with new hooks any which may become damaged.

Having thus described my invention, I claim:

1. A body drag consisting of a triangular frame with a number of double pointed hooks alternately long and short, evenly spaced across the frame of the drag and attached to the frame by means of stove bolts.

2. A body drag consisting of a triangular frame made from two pieces of round iron joined by a piece of angle iron with an eye at the point where the two pieces of round iron meet; attached to the angle iron, extending downward therefrom, nine double-pointed, barbed metal hooks spaced five inches apart, said hooks being alternately five inches and two inches long.

3. A body drag as above claimed having two single, barbed hooks joined back to back by soldering; nine so constructed double-pointed hooks spaced five inches apart covering the width of the frame or, in other words, the length of the angle iron.

4. A body drag consisting of a triangular frame made of two pieces of round iron joined by a piece of angle iron, having an eye for the insertion of a drag rope where the ends of the round iron meet; attached to the angle iron by means of bolts nine double-pointed barbed metal hooks alternately two inches and five inches long.

In testimony whereof, I have signed my name to this specification.

TIMOTHY J. DILWORTH.
